UNITED STATES PATENT OFFICE

99,603

DESIGN FOR A CORNER ORNAMENT FOR A CASKET OR ANALOGOUS ARTICLE

Raymond Larson, Chicago, Ill., assignor to Central Metallic Casket Co., Chicago, Ill., a corporation of Illinois

Application August 17, 1935, Serial No. 58,186

Term of patent 7 years

To all whom it may concern:

Be it known that I, Raymond Larson, a citizen of the United States, residing at 2207 North Lamon Avenue, Chicago, in the county of Cook and State of Illinois, have invented a new, original, and ornamental Design for a Corner Ornament for a Casket or Analogous Article, of which the following is a specification, reference being had to the accompanying drawing, forming part thereof:

Figs. 1 and 2 are elevational views showing opposite sides of the corner ornament embodying my design; and

Fig. 3 is a top plan view thereof.

I claim:

The ornamental design for a corner ornament for a casket or analogous article as shown.

RAYMOND LARSON.
